CASTING FURNACE

Willis A. Aschoff, Albany, Oreg., assignor to Oregon Metallurgical Corporation, Albany, Oreg., a corporation of Oregon

Application April 22, 1957, Serial No. 654,292

13 Claims. (Cl. 13—10)

This invention relates to casting furnaces and more particularly to casting furnaces useful for the production of metal castings from refractory metals wherein the metal castings are prepared under carefully controlled operating conditions.

In preparing castings from metals such as titanium and zirconium, the conditions under which the metal is reduced to a molten state, and subsequently cooled, must be carefully controlled to eliminate contamination of the metal and/or destruction of the apparatus employed. While relatively stable at lower temperatures, titanium, for example, quickly reacts with such materials as oxygen and nitrogen at elevated temperatures with the formation of compounds which deleteriously affect the properties of the metal. Consequently, titanium is usually handled at elevated temperatures either in a vacuum or in the presence of an inert gas such as argon or helium.

In addition to the atmospheric conditions employed, the materials and temperatures of the vessels and equipment used during a melt must also be carefully selected. Many of the ordinary metals, for instance, react with titanium at elevated temperatures contaminating the metal and impairing its physical properties. Further, the relatively high melting point of titanium, which is approximately 1800° C., requires that some form of cooling be supplied any vessel holding the molten metal if the vessel is comprised of material having a melting point lower than that of titanium.

A method presently used for preparing titanium and zirconium castings comprises heating the metal by means of an electric arc in a sealed furnace chamber from which air has been evacuated. Considering titanium, for example, the titanium is first formed into an elongated bar which functions as one of the pair of electrodes necessary for producing an electric arc. The electric arc is generated between the end of the titanium bar which is melted or consumed during the process and the vessel in which the molten titanium is collected, this vessel constituting the other of the pair of electrodes in the process. Such a process uses relatively large amounts of electric current delivered at relatively low voltages, a typical operation employing a direct current of 10,000 amps. at a voltage of approximately 30 volts. Molten metal is poured from the collecting vessel into appropriate molds as soon as possible after terminating the electric arc to prevent the metal from freezing within the vessel. The metal casting is then allowed to cool preferably with the introduction of an inert gas into the furnace chamber which facilitates cooling without reacting with hot titanium.

Because of the relatively large electrical current employed, the electrical components of the electrical circuit producing the arc in such a furnace preferably are made of a highly conductive material such as copper to eliminate power losses in these components. The rod or "stinger" normally used for lowering the titanium electrode into the furnace also serves to deliver current to the titanium electrode carried at its lower end and there-

2

fore is conventionally comprised of copper. Similarly, the circuit for the other electrode in the furnace, comprising the vessel holding the melt and the connections between this vessel and one of the pair of power supply conductors in a plant, is also normally comprised of copper. Copper has a melting point considerably below that of titanium so a copper vessel holding molten titanium must be cooled to prevent destruction of the vessel. A water circulating system is normally used for this purpose. In practice, the initial titanium melt forms a solidified hollow "skull" around the interior of the vessel which insulates the vessel from the pool of molten titanium collected in the skull.

The creation intermittently of a vacuum within the furnace, the necessity for having an electrical path of low resistance for the current producing the arc in the furnace, and the requirement that the vessel holding the melt be cooled during operation of the furnace, has created a number of problems. The vessel or crucible holding the melt is normally pivotally mounted within a furnace chamber to enable a pour to be made by tilting the vessel. Furnace constructions heretofore have used flexible conductors interconnecting the vessel and the power supply in a plant to accommodate pivotal movement of the vessel. The conduit systems employed for delivering coolant to the vessel have either used flexible hosing or resorted to swivel connections within the furnace to permit pivoting of the vessel. Further, the mechanism used for tilting the vessel has customarily been mounted within the interior of the furnace to eliminate difficulties in maintaining a vacuum in the furnace. Such constructions, however, have been troublesome by reason of the operating conditions within the furnace. Molten metal splashing deposited upon the flexible electrical conductors cause the conductors to become brittle and, by so doing, severely limit the life of the conductors. Flexible hose connections delivering coolant to the vessel have been a constant source of potential leaks causing shutdowns and wasted man hours. The presence of swivel joints and moving mechanical parts has been undesirable since metal particles have tended to lodge themselves within the mechanisms, creating frequent failures. This latter problem is particularly acute because of the "breathing" action which takes place in mechanisms such as swivel joints created by sequentially creating a vacuum and then restoring atmospheric pressure within the furnace.

Generally, it is an object of this invention to provide a novel means for supporting and canting a ladle or crucible within a casting furnace which eliminates the necessity of using flexible conductors or hosing within the furnace.

More specifically, it is an object of this invention to provide a casting furnace for producing metal castings as described above, wherein the ladle or crucible collecting the molten metal for the castings is canted or tilted within the furnace by means of a canting arm affixed to the ladle and projecting outwardly to the exterior of the furnace, and to provide a novel means for rotating such a canting arm.

A further object of this invention is to provide such a furnace construction wherein the canting arm, together with the ladle, constitutes a portion of the electrical circuit for the production of the electric arc within the furnace, the connection between the canting arm and the electrical power supply in a plant being established outside the furnace.

Further, it is an object of this invention to provide such an electric arc furnace wherein the canting arm includes passage means supplying a coolant to the ladle mounted within the furnace thereby eliminating the need for swivel joints within the furnace.

Further, it is an object of this invention to provide a casting furnace, having a canting arm of the type described which includes power actuated means for rotating the canting arm and a novel means inhibiting rotary movement of the canting arm beyond limit positions to either side of a base position, wherein the ladle occupies an upright position within the furnace.

Another object of this invention is to provide a casting furnace wherein the ladle or crucible for the furnace is rotatably supported within the furnace by means of a pair of axially aligned, tubular shaft sections disposed on either side of the ladle with opposite ends of the shaft sections protruding outside the furnace, the shaft sections constituting a portion of the electric circuit producing an electric arc within the furnace, providing discharge and exhaust connections for coolant supplied to the ladle, and providing a motion transmitting mechanism for imparting a tilt to the ladle when a pour is to be made.

These and other objects and advantages are attained by the present invention, various novel features of which will become more fully apparent as the following description is read in conjunction with the accompanying drawings wherein:

Fig. 1 is a side view of a casting furnace embodying the present invention;

Fig. 2 is a section view along the line 2—2 in Fig. 1;

Fig. 3 is an enlarged section view along the line 3—3 in Fig. 2, showing the construction used for affixing one of the canting arms or shafts to the ladle within the furnace;

Fig. 4 is an enlarged section view along the line 4—4 in Fig. 1, illustrating a pressure seal employed in the furnace;

Fig. 5 is an enlarged section view along the line 5—5 in Fig. 1; and

Fig. 6 is a schematic view of the means employed for rotating the ladle or crucible within the furnace.

In the drawings, where an embodiment of this invention is illustrated, 9 indicates generally an electric arc furnace comprising a furnace body portion indicated at 10, a shielding sleeve or "stack" 11 affixed to the top of the furnace body and projecting vertically upwardly therefrom, and a rod or "stinger" 12 mounted for reciprocation up and down in stack 11. Stinger 12 has a consumable metal electrode such as a titanium electrode 13 secured to and in electrical contact with the lower end of stinger 12. This connection may be made in a conventional manner such as by securing electrode 13 onto a threaded stud carried at the lower end of stinger 12. Stinger 12 provides a means for lowering the titanium electrode downwardly within the furnace as the electrode is progressively melted away by the heat generated in the electric arc.

As illustrated, body portion 10 of the furnace is comprised of furnace shell portions 16, 17, and 18, which may be disassembled from each other to accommodate entry into the interior of the furnace. Each of the shell portions is comprised of a pair of metal jackets illustrated by jackets 19 and 21 of furnace shell 18. Jackets 19 and 21 are spaced from each other by suitable bracing structure disposed between the jackets. Chamber 23 defined between the jackets may be filled with water or other coolant when it is desired to reduce or otherwise control the temperature within the furnace as for instance when cooling the furnace prior to removing a finished casting. In the case of a titanium casting, since titanium is reactive with air at temperatures much above 800° C., the interior of the furnace usually is lowered below this temperature before introducing air into the furnace.

Furnace shells 16, 17, and 18 are secured together in substantially a pressure-tight relationship by means of clamping members 24. Clamping members 24 grip the outer faces of flanges 22 and 25 carried by the furnace

shell portions. As best seen in Fig. 5, a pressure-tight seal may be readily obtained by including between the inner or pressure faces of flanges 22, 25 an annular sealing member, such as an O-ring 20, which is compressed between the flanges by tightening members 24. The O-ring seats in an annular groove formed in the inner face of one of the flanges.

A turret portion 26 projects upwardly from center furnace shell 17 with the interior of turret 26 in communication with the interior of the furnace. Shielding sleeve or stack 11 is secured to the top of turret 26 by clamping together flanges 27 and 28 carried by the stack and the turret, respectively, with a set of clamping members 29. Referring to Fig. 2, a pressure-tight seal between these members is obtained by clamping the flanges together about an O-ring in a manner similar to the assembly of the furnace shells.

Shielding sleeve 11 is relatively long, enabling the use of a relatively long titanium-electrode. As the electrode is consumed, the electrode is lowered into the furnace by lowering stinger 12 in shield 11.

Secured to the top of sleeve 11, as by clamps 31, is a stinger guide element 32. Stinger guide 32 includes a hub section 33, encompassing stinger 12 and vertically aligning the stinger in stack 11, and a flange 38. During melting under vacuum, clamps 31 may be removed, enabling element 32 to serve as an explosion blow-off cap. Interposed between flange 38 and a flange 39 of shielding sleeve 11 is an annular electric insulating ring 41. Insulating ring 41 insulates stinger guide 32 and stinger 12, which carries the electric current for producing the arc in the furnace, from sleeve 11 and the body of the furnace. In the embodiment illustrated, the electrical connection between the stinger and one of the pair of power supply conductors in a plant is made by two sets of flexible cables 42 extending from diametrically opposed portions of stinger 12. The cables ordinarily are water cooled to increase their current capacity. By using two sets of cables, movement of the cables because of any magnetic field set up in the cables tends to be nullified. Cables 42 are secured at one end to the power supply conductor, which may take the form of a bus bar (not shown), and at their other end to a clamp member 43 clamped about and tightly contacting the upper end of stinger 12.

Stinger 12 is raised and lowered within the furnace and the shielding sleeve or stack by any suitable means such as winch 46 and cable 47. In the casting of titanium, molten titanium should be poured into the mold relatively soon after the arc within the furnace is cut off and before appreciable cooling of the molten metal takes place. Mechanism is included for rapidly withdrawing the titanium electrode from the interior of the furnace so as to raise the lower end of the electrode free of the vessel containing molten metal and thus enable the vessel to be tilted without striking the lower end of the electrode. This mechanism includes an expandable fluid motor 45 having cylinder 48 affixed to suitable support structure and a piston 49 carrying a pulley 51 riding on a horizontal portion of cable 47. Retraction of piston 49 sharply downwardly within the cylinder functions to lower pulley 51 so as to abruptly raise the stinger within furnace body 10.

Referring to Fig. 4, stinger 12 is slidably mounted within stinger guide 32 by means of a packing gland 52 and sealing ring 53. This construction accommodates slidable movement of the stinger while maintaining a substantially pressure-tight seal around the stinger.

As can be best seen in Fig. 2, positioned below the lower end of electrode 13 is a ladle means indicated generally at 61. The ladle is mounted to be tilted or canted to either side of an upright position when a pour is made from the ladle. Molten titanium is poured from the ladle into a conventional mold indicated by dotted

lines at 62 supported on a table 63 within the furnace chamber.

Ladle 61 is supported within the interior of the furnace chamber by a pair of tubular shaft sections or canting arms 64 and 66 axially aligned with one another and mounted for rotation about their longitudinal axes relative to the side walls of furnace shell 17. The shaft sections are made of electrically conductive material, such as copper, the shaft sections together with ladle 61 forming part of the circuit for the production of the electric arc in the furnace. The shaft sections are non-rotatably affixed at their inner ends to ladle 61, and the outer ends of the shafts project outside of furnace body 10. The ladle is tilted by rotating the shafts from a point outside the furnace, the shaft sections thereby functioning as a motion transmitting mechanism for canting the ladle within the furnace. Cooling water for the ladle is introduced into the interior of the shaft sections from an inlet point located outside the furnace. By the construction employed, the use within the furnace of flexible conductors, flexible hose connections, swivel connections, or motor mechanism for tilting the ladle may be done away with.

More specifically, ladle 61 comprises an inner container portion 67 and an outer jacket portion 68 spaced from each other to present thereinbetween a cavity 69. Inner container portion 67 and jacket portion 68 are comprised of copper, save for a lower portion 70 which is comprised of steel and welded at 65 to the ladle. Ladle 61 provides a path for the current producing the arc in the furnace. Container portion 67 has walls which incline inwardly from the top of the container and a rounded bottom enabling the easy removal of the solidified "skull" of titanium which normally forms on the surface of the container portion during the melting operation. Such a skull forms by reason of the fact that the walls of the container are cooled below the melting point of titanium to prevent the copper portions of the ladle from melting. The rounded bottom of container portion 67 more or less conforms to the curvature of the skull which forms, thereby reducing the build-up of large deposits of solidified titanium in the skull.

To either side of jacket portion 68 are a pair of copper tubular stub sections 71 and 72 which are connected at their outer ends to the inner ends of tubular shaft sections 64 and 66. With reference to Fig. 2, a conduit 73 connects intermediate portions of stub section 72 to the bottom of outer jacket 70. A wall 74 extends across the inner end of stub section 72 so that coolant introduced through the interior of shaft section 66 is deflected by wall 74 downwardly through conduit 73 into cavity 69. A baffle 76 directs the coolant upwardly and out of cavity 69, the coolant flowing around baffle 76 through stub section 71 and out of the furnace through shaft section 64.

Shaft sections 64, 66 are connected to stub sections 71, 72 by the detachable connection best illustrated in Fig. 3. Referring to Fig. 3, each of the shaft sections carries at its inner end a flange 77, and each of the stub sections carries at its outer end a flange 78. These flanges are bolted together by bolts 79 in tight electrical contact with each other. Clamping rings 81 and 82, comprised of steel or some other such material, are included to insure adequate electrical contact between the relatively soft copper flanges. The interiors of the stub and shaft sections carry coolant for ladle 61 so a water seal is included between the flanges. A groove 83 extending about the circumference of flange 77 seats on an O-ring 84 which is compressed between the flanges when the flanges are juxtaposed. Groove 83 is roughly two-thirds the depth of the O-ring so that the O-ring is resiliently deformed as shown in Fig. 3 when the flanges are pressed together.

The inner ends of shaft sections 64 and 66 are rotatably supported within the furnace in hanger brackets

86, 87. Intermediate portions of the shaft sections are supported in the walls of the furnace in sleeve segments 88 and 89 affixed to furnace body 10. A substantially pressure-tight seal is created between the shaft sections and sleeve segments by means of packing glands 91, 92 and suitable packing material surrounding the shaft sections and compressed against the shaft sections by the packing glands.

A swivel joint, such as swivel joint 95, connects the outer end of each shaft section to suitable conduits supplying and discharging cooling water to ladle 61. The swivel joint permits rotation of the shaft sections relative to the water supply and exhaust conduits and are conventional in construction.

Affixed to each of the shaft sections inwardly from the swivel joints, and outside the furnace walls, are a pair of conductor clamps 99 and 100, respectively. Each clamp surrounds a shaft section and has a pair of ends which are pulled together by bolts 101. Flexible conductors 102 connect each conductor clamp to the other of the pair of power supply conductors in a plant. The electric circuit for producing an arc in the furnace comprises, therefore, conductor 42 connected to one of the power supply conductors, stinger 12, electrode 13, ladle 61, shaft sections 64 and 66, and conductors 102 which are connected to the other of the supply conductors. By using diametrically opposed conductor connections to ladle 61, represented by shaft sections 64, 66, the arc produced in the furnace tends to be centered in the ladle.

Referring again to Fig. 1 and Fig. 2, a sprocket 103 affixed to shaft section 64 and a drive chain 104 provide a means for rotating the shaft segments about their longitudinal axes to either side of a base position for the shaft segments, ladle 61 carried by the inner ends of the shaft segments occupying an upright position when the shaft sections are in their base position. A motor 106 and a sprocket 105 power the drive chain and sprocket 103.

Projecting inwardly from a plate 111 secured to rotate with sprocket 103 is a finger 112. In the path of finger 112 as it rotates with shaft section 64 are three switches, a basing switch 113 and a pair of limit switches 114, 115, spaced below switch 113. Limit switch 115 is obscured in Fig. 2. The basing switch operates to automatically turn off the power supply for electric motor 106 for a certain time interval when shaft section 64 is rotated into its base position from a position to either side of the base position. The two limit switches shut off the power supply for motor 106 when shaft 64 is rotated to either one of a pair of limit positions located to either side, respectively, of the base position for the shaft. The limit switches stop the tilting of the ladle at predetermined optimum pouring positions.

Referring to Fig. 6, wherein the control system for motor 106 is set forth schematically, power for motor 106 is delivered through a pair of conductors 121, 122. The motor is conventional, rotating counterclockwise in Fig. 6 when a switch 123 is closed and rotating clockwise in Fig. 6 when a switch 124 is closed. A pair of conductors 126, 127 supply the current controlling the operation of switches 123, 124.

Switch 113 connected to conductor 126 has a pair of switch contacts 128 and 129. Switch contact 129 is connected through a thermal element 131 to conductor 127, thermal element 131 closing a switch 132 after a predetermined time delay.

Connected by a conductor 135 to switch 132 are a pair of push button switches 133 and 134, respectively. When shaft 64 occupies its base position, switch point 137 of switch 113 engages switch contact 129 and thermal element 131 is energized. After the expiration of a time delay, switch 132 is closed and motor 106 may be driven either in a clockwise or counterclockwise direction by closing one of the pair of switches 133, 134. If switch 133 is closed, current flows through conductor 75 135, the solenoid ganged to switch 123, switch 114, and

conductor 127, so that switch 123 closes and rotation of motor 106 is in a counterclockwise direction. If switch 134 is closed, current flows through conductor 135, the solenoid ganged to switch 124, switch 113, and conductor 127, so that switch 124 closes and rotation of motor 106 is in a clockwise direction.

As long as either switch 133 or 134 is closed, rotation of the motor continues until finger 112 reaches one of the pair of limit switches 114, 115. After shaft 64 is rotated away from its base position, switch point 137 of switch 113 engages switch contact 128 which completes the circuit between conductor 126 and conductor 135.

If shaft 64 is positioned to either side of its base position and it is desired to return the shaft to its base position, return rotation of the shaft is brought about by closing the appropriate one of the pair of push button switches 133, 134. For instance, if the shaft should be rotated in a clockwise direction in order to return the shaft to its base position, closing push button switch 134 brings about the desired rotation. Rotation of the shaft continues in a clockwise direction until the shaft reaches its base position at which time switch point 137 engages switch contact 129 of switch 113, the solenoid ganged to switch 124 is de-energized, and switch 124 opens. If push button switch 134 remains closed, rotation of shaft 64 continues after switch 132 is closed by thermal element 131. The time delay in the circuit enables an operator accurately to position shaft 64 in its base position while permitting the operator to make pours to either side of the base position if desired.

A pair of switches 138 and 139 connected between conductor 135 and the solenoids controlling operation of switches 123, 124 are included to provide a means for remotely controlling the operation of motor 106. These switches customarily would be located some distance away from push button switches 133, 134.

Included in the furnace are a pressure gauge 141 (Fig. 2) and a conduit 142 for introducing an inert gas into the furnace when it is desired to reduce the temperature within the furnace. An exhaust conduit 143 (Fig. 1) connected to a suitable vacuum generator (not shown) is also provided for evacuating the atmosphere from within the furnace. A fan may also be included within the furnace to increase the cooling rate within the furnace.

While there has been described an embodiment of this invention, it is not intended to be limited thereby, and it is desired to cover all modifications which would be apparent to one skilled in the art and that come within the scope of the appended claims.

It is claimed and desired to secure by Letters Patent:

1. An electric arc furnace for the production of metal castings comprising a furnace body having walls defining an enclosed furnace chamber, a pair of electrodes within the interior of the furnace for producing an arc therein, one of the latter taking the form of ladle means, and canting means for tilting said ladle means, said canting means comprising a canting arm extending through a wall of said furnace body and mounted for rotation relative thereto, an inner portion of said arm being secured to and in electrical contact with said ladle means and an outer portion of said arm projecting outside of said furnace chamber, said canting arm having a conductor portion providing an electrical path between said inner and outer portions of said arm, said conductor portion constituting a part of the electrical circuit for the production of an electric arc in said furnace, rotation of said outer portion of said canting arm tilting said ladle means.

2. A furnace for the production of metal castings comprising a furnace body having walls defining an enclosed furnace chamber, a pair of electrodes within the interior of the furnace for producing an arc therein, one of the latter taking the form of ladle means, said ladle means having circulating passage means circulating a

coolant for said ladle means, and canting means for tilting said ladle means, said canting means comprising a canting arm extending through a wall of said furnace and mounted for rotation relative thereto, an inner portion of said arm being secured to and in electrical contact with said ladle means and an outer portion of said arm projecting outside of said furnace chamber, and fluid transfer passage means in fluid communication with said circulating passage means and extending within said canting arm between said circulating passage means and said outer portion of said arm, said canting arm having a conductor portion providing an electrical path between said inner and outer portions of said arm, said conductor portion constituting a part of the electrical circuit for the production of an electric arc in said furnace, rotation of said outer portion of said canting arm tilting said ladle means.

3. An electric arc furnace for the production of metal castings comprising a furnace body having walls defining an enclosed furnace chamber, a pair of electrodes within the interior of the furnace for producing an arc therein, one of the latter taking the form of ladle means, said ladle means having circulating passage means circulating a coolant for said ladle means, and canting means for tilting said ladle means, said last canting means comprising a canting arm comprised of electro-conductive material rotatably mounted in and extending through a wall of said furnace body, an inner portion of said arm being secured to and in electrical contact with said ladle means and an outer portion of said arm extending outside of said furnace chamber, fluid transfer passage means in fluid communication with said circulating passage means and extending within said canting arm between said circulating passage means and said outer portion of said arm, and electrical conductor means connected to said outer portion of said canting arm, said canting arm and conductor means constituting a part of the electrical circuit for the production of an electric arc in said furnace, rotation of said outer portion of said canting arm tilting said ladle means.

4. The electric arc furnace of claim 3 which further comprises power driven actuating means connected to said outer portion of said canting arm operable to rotate said canting arm so as to tilt said ladle means, and means limiting rotation of said canting arm by said actuating means beyond a pair of limit positions located to either side of a base position for said arm, respectively, said canting arm in said base position supporting said ladle means in an upright position within said chamber.

5. A casting furnace for the production of metal castings comprising a furnace body having walls defining an enclosed furnace chamber, ladle means within the interior of said furnace chamber, said ladle means having circulating passage means circulating a coolant for said ladle means, and canting means for tilting said ladle means, said canting means comprising a canting arm extending through a wall of said furnace body and mounted for rotation relative thereto, an inner portion of said arm being secured to said ladle means and an outer portion of said arm projecting outside of said furnace chamber, fluid transfer passage means in fluid communication with said circulating passage means and extending within said canting arm between said circulating passage means and said outer portion of said arm, power driven actuating means connected to said outer portion of said arm operable to rotate said canting arm so as to tilt said ladle means, and means limiting rotation of said canting arm by said actuating means beyond a pair of limit positions located to either side of a base position for said arm, respectively, said canting arm in said base position supporting said ladle means in an upright position within said furnace chamber.

6. The casting furnace of claim 5 which further includes means for positioning said canting arm in said base position.

7. In an electric arc casting furnace having furnace wall portions defining an enclosed furnace chamber and ladle means disposed within the interior of said chamber, said ladle means having circulating passage means circulating a coolant for said ladle means, canting means for tilting said ladle means and enabling a pour to be made from said ladle means, said canting means comprising a pair of axially aligned tubular shaft sections nonrotatably affixed at their inner ends to opposite sides of said ladle means, respectively, outer end portions of said shaft sections projecting outside of said furnace chamber, the interior of each of said tubular shaft sections connecting with said circulating passage means and providing a fluid transfer passage for coolant circulated in said ladle means, rotation of said outer end portions of said shaft sections tilting said ladle means.

8. In an electric arc casting furnace having furnace wall portions defining an enclosed furnace chamber, a pair of electrodes within the interior of the furnace for producing an arc therein, one of the latter taking the form of ladle means, the improvement comprising canting means for tilting said ladle means and enabling a pour to be made from said ladle means, said canting means comprising a pair of axially aligned shaft sections nonrotatably affixed at their inner ends to opposite sides of said ladle means, respectively, outer end portions of said shaft sections projecting outside of said furnace chamber, at least one of said shaft sections being comprised of electro-conductive material, and electrical conductor means connected to the outer end portion of said one of said shaft sections, said one of said shaft sections and said conductor means constituting a part of the electrical circuit for the production of an electric arc in said furnace, rotation of said outer end portions of said shaft sections tilting said ladle means.

9. In an electric arc casting furnace having furnace wall portions defining an enclosed furnace chamber, a pair of electrodes within the interior of the furnace for producing an arc therein, one of the latter taking the form of ladle means, said ladle means having circulating passage means circulating a coolant for said ladle means, the improvement comprising canting means for tilting said ladle means and enabling a pour to be made from said ladle means, said canting means comprising a pair of axially aligned tubular shaft sections nonrotatably affixed at their inner ends to opposite sides of said ladle means, respectively, outer end portions of said shaft sections projecting outside of said furnace chamber, the interior of each of said tubular shaft sections connecting with said circulating passage means and providing a transfer passage means for coolant circulated in said ladle means, at least one of said shaft sections being comprised of electro-conductive material, and electrical conductor means connected to the outer end portion of said one of said shaft sections, said one of said shaft sections and said conductor means constituting a part of the electrical circuit for the production of an electric arc in said furnace.

10. The apparatus of claim 9 wherein each of said tubular shaft sections is affixed to said ladle means by means of a detachable connection.

11. The apparatus of claim 10 wherein said detachable connection comprises co-operating annular flange portions presented by the shaft section and said ladle means, respectively, oppositely disposed faces of said flanges abutting each other to provide electrical contact, one of said flange portions having an annular groove therein accommodating an annular sealing member disposed between said flange portions, said annular sealing member being resiliently deformed by juxtapositioning said flange portions.

12. An electric arc casting furnace comprising a set of furnace shell sections secured together in substantially pressure-tight relationship and defining within said shell sections an enclosed furnace chamber, means for producing a vacuum within said chamber, a pair of electrodes within the interior of the furnace chamber for producing an arc therein, one of the latter taking the form of ladle means, said ladle means having circulating passage means circulating a coolant for said ladle means, and canting means for tilting said ladle means while maintaining said chamber under vacuum, said canting means comprising a pair of axially aligned tubular shaft sections nonrotatably affixed at their inner ends to opposite sides of said ladle means, respectively, outer end portions of said shaft sections projecting outside of said furnace chamber, the interior of each of said tubular shaft sections connecting with said circulating passage means and providing a transfer passage means for coolant circulated in said ladle means, at least one of said shaft sections being comprised of electro-conductive material, and electrical conductor means connected to the outer end portion of said one of said shaft sections, said one of said shaft sections and said conductor means constituting a part of the electrical circuit for the production of an electric arc in said furnace.

13. An electric arc casting furnace comprising a set of furnace shell sections secured together in substantially pressure-tight relationship and defining within said shell sections an enclosed furnace chamber, means for producing a vacuum within said chamber, a pair of electrodes within the interior of the furnace chamber for producing an arc therein, one of the latter taking the form of ladle means, said ladle means having circulating passage means circulating a coolant for said ladle means, and canting means for tilting said ladle means while maintaining said chamber under vacuum, said canting means comprising a pair of axially aligned tubular shaft sections nonrotatably affixed at their inner ends to diametrically opposed sides of said ladle means, respectively, said inner ends of said shaft sections being in tight electrical contact with said ladle means, outer end portions of said shaft sections projecting outside of said furnace chamber, means for rotating said outer end portions of said shaft sections, the interior of each of said shaft sections connecting with said circulating passage means and providing a transfer passage means for coolant circulated in said ladle means, each of said shaft sections being comprised of electro-conductive material, and electrical conductor means connected to the outer end portions of each of said shaft sections, said ladle means, shaft sections, and conductor means constituting a part of the electrical circuit for the production of an electric arc in said furnace, said shaft sections providing diametrically opposed branches in said electrical circuit operable to center the arc in said furnace.
